UNITED STATES PATENT OFFICE.

JOHN WILLIS, OF KANE, PENNSYLVANIA, ASSIGNOR TO AMERICAN PLATE GLASS COMPANY, OF KANE, PENNSYLVANIA, A CORPORATION OF NEW JERSEY.

SAND-GRADING APPARATUS.

1,246,202.

Specification of Letters Patent. Patented Nov. 13, 1917.

Application filed November 15, 1916. Serial No. 131,401

To all whom it may concern:

Be it known that I, JOHN WILLIS, a citizen of the United States, residing at Kane, in the county of McKean and State of Pennsylvania, have invented certain new and useful Improvements in Sand-Grading Apparatus, of which the following is a specification.

This invention refers to an improvement 10 in glass grinding apparatus for the purpose of supplying sand or other abrasive material used in grinding plate glass or other similar material, so that it may be furnished to the usual rotatable table in successively 15 progressing grades of fineness. The invention also has in view to effect an economy in the sand, avoiding any unnecessary loss, and reducing the cost of the process carried out by the apparatus to a minimum. Another 20 object of the invention is to so apply the sand to the grinding table as to most effectively secure reduction of the surface to a substantial plane in condition ready for the polishing operation, in the shortest time.

25 Referring to the drawings illustrating the invention:—Figure 1 is a view in sectional elevation showing the apparatus as applied to a sand grinding table.

Fig. 2 is a plan view of Fig. 1.

30 Fig. 3 is a detail plan view showing the adjustable terminal of the abrasive conducting pipe leading into the first of the five sand hoppers.

Fig. 4 is a similar view showing a modified arrangement for changing the circulation.

The sand grinding table 2 is rotatably mounted in the usual way and in connection with the rotatable runners 3, 3, having the 40 customary raising and lowering mechanism not herein shown. Located adjacent to the table and extending downwardly to any desired depth below it, is a main sump pit 4 having a transverse vertical partition 5 dividing the pit into a primary chamber *a* and a secondary chamber *b*. A gutter 6 collects the over-flow from table 2 and by a channel 7 deposits all of the collected water and abrasive into the upper portion of chamber 45 *a* of sump pit 4, any overflow passing off from the top to the sewer by a conduit 8.

A pump 9, which is preferably a rotary pump and made of any suitable construction, is provided with an intake connection 50 extending through the partition 5 into

chamber *a* and a conduit 11 leads from pump 9 in chamber *b* upwardly over across the table, conduit 11 is provided with a delivery terminal 12, preferably adjustable for delivery into a return conduit 13 or into the 60 first of a series of settling compartments 14, 14^a, 14^b and 14^c. Conduit 13, on the other hand, may itself be adjustable so as to be shifted over, by its receiving terminal box 13^a, into register with the delivery terminal 65 12 or away from it, as will be readily understood. Adjustability of conduit 12 is made by using the usual elbow or other suitable pipe fittings as shown.

The several settling compartments 14, 14^a, 70 14^b and 14^c are of any suitable construction but preferably hopper-shaped, terminating in diminished tapering delivery bottom portions, with each of which is connected a branch outlet conduit 15, having a control 75 valve 15^a and leading into a common manifold pipe 16. Said pipe is connected with a suitable pump 17 having a delivery pipe 18 leading over to the distributing trough 19 above and between the runners, into which 80 the pipe 18 also discharges.

As shown, the settling chambers or hoppers 14, 14^a, 14^b and 14^c are provided with an inner wall 14^d which closely approximates the curvature of the main grinding table, 85 providing for economical installation, while also securing the desirable successive widening of the several hoppers toward the end-most overflow outlet.

In operation, a charge of coarse sand is 90 first deposited in chamber *a* of the sump pit with an ample supply of water, and the pump 9 is put into operation, carrying the coarse sand upwardly by conduit 11 to delivery pipe 13 which receives it by its box 95 13^a and discharges it down onto the grinding table.

The sand is there used with the usual water supply, acting as an abrasive under the runners, all of the used sand and water 100 returning to the sump pit in a partly used condition and with some or all of the grains reduced in size. From time to time additional coarse sand may be supplied, as needed. After such operation is continued for 105 a sufficient length of time known as the "coarse grinding" the sand now reduced to more or less fine form, is delivered into the first compartment 14 of the series of settling compartments and is collected in each com- 110

partment in a graded condition, due to the lateral flow of the water carrying the sand in suspension over toward the overflow 20 having the return pipe 21. Any surplus 5 water and useless slimes or other waste material are carried off to the sewer either by overflow or by deflecting pipe 21 to a sewer connection. The remaining useful sands are deposited by precipitation into the several 10 collecting compartments 14, 14^a, 14^b and 14^c respectively. Commencing with the coarser of the fine sand in the first compartment, and by means of pump 17 and its connections above described, the first grade of fine 15 sand is used and the next finer grades are successively used and applied to the table, the operation being continued until the finest sand has been applied, when the grinding operation is ordinarily finished and the glass 20 is ready for the finishing operation.

It is not essential in carrying out the above described operation that the original batch of coarse sand be maintained to the exclusion of any additional sand, as fresh 25 coarse sand may be supplied from time to time to the compartment α of the sump pit depending upon the requirements for the coarse grinding. Also from time to time the conduit 13 may be used to deposit any of 30 the finer grades of sand in the settling compartments and the operations of grinding and settling may occur simultaneously or intermittently when desired.

The present invention is similar in certain 35 respects to my prior application filed Oct. 18, 1915, Serial No. 56,348.

What I claim is:

1. In combination with a glass grinding table, a main sump pit adapted to receive 40 the overflow therefrom and to receive fresh abrasive at its upper end, means for removing coarse abrasive and water from the sump pit and having a conduit adapted to be put in connection with a conduit leading back 45 to the table or with a settling compartment, a co-acting conduit leading back to the table, a series of grading compartments adapted to receive abrasive and water from the sump pit conduit and to collect the abrasive in 50 varying grades by precipitation and provided with a terminal overflow, a pump, a conduit connected with said pump and with the bottom of each of the grading compartments, and a delivery pipe leading from the 55 pump to the table.

2. In combination with a glass grinding table, a sump pit adapted to receive overflow from the table and abrasive at its upper portion, a series of settling compartments, and 60 means for withdrawing the contents of each compartment separately and delivering the same to the table; a return conduit leading

back to the table and a pump adapted to take abrasive and water from the sump pit and provided with a terminal adapted to be 65 put into communication with said return conduit or with the first of said settling compartments.

3. In combination with a glass grinding table, a sump pit adapted to receive overflow 70 from the table and abrasive at its upper portion, a series of settling compartments, and means for withdrawing the contents of each compartment separately and delivering the same to the table; a return conduit leading 75 back to the table and provided with a movable receiving terminal, and a pump adapted to take abrasive and water from the sump pit and provided with a terminal adapted to be put into communication with said receiving terminal or with the first of said settling compartments.

4. In combination with a glass grinding table, a sump pit adapted to receive overflow 85 from the table and abrasive at its upper portion, a series of settling compartments, and means for withdrawing the contents of each compartment separately and delivering the same to the table; a return conduit leading back to the table and provided with a receiving terminal, a pump adapted to take abrasive and water from the sump pit provided with a delivery conduit, one of said conduits being adjustable whereby the pump conduit is adapted to be put into communication 90 with the terminal of said return conduit or with the first of said settling compartments.

5. In combination with a glass grinding table and a conduit adapted to deliver abrasive and water to the table; a sump pit 100 adapted to receive overflow from the table and abrasive at its upper portion, a pump compartment adjacent the sump pit and partitioned therefrom, and a pump in said compartment communicating with the sump pit 105 and having a conduit adapted to be put into direct communication with the return conduit leading back to the table.

6. In combination with a circular glass grinding table, a single-chamber collecting 110 sump pit, means for removing the contents of the sump pit and for delivering the same back to the table or to the first of a series of settling compartments; a series of such compartments having an outer straight wall 115 and an inner wall diverging therefrom and substantially conforming to the curvature of the table, an overflow therefor, and means for removing the contents of each compartment separately and supplying the same to 120 the table.

In testimony whereof I hereunto affix my signature.

JOHN WILLIS.
